UNITED STATES PATENT OFFICE.

HENRY H. ROBERTS, JR., OF PHILADELPHIA, PENNSYLVANIA.

TELLTALE DEVICE FOR AUTOMOBILE-TIRES.

RE'ISSUED

1,208,659.

Specification of Letters Patent. Patented Dec. 12, 1916.

Application filed December 4, 1915. Serial No. 65,152.

To all whom it may concern:

Be it known that I, HENRY H. ROBERTS, Jr., a citizen of the United States, residing at the city of Philadelphia, in the county of 5 Philadelphia and State of Pennsylvania, have invented certain new and useful Improvements in Telltale Devices for Automobile-Tires, of which the following is a specification.

10 My invention has relation to a simple and effective tell-tale device mounted in the shoe of a motor vehicle tire so as by frictional wear of a rolling body therein to ascertain the extent of use to which the tire has been 15 subjected or the distance the same has traversed; and to which end my said invention, consists of a device constructively arranged for use in a shoe in the manner hereinafter described and claimed.

20 The nature and scope of my present invention will be more fully understood from the following description taken in connection with the accompanying drawings forming part hereof, in which—

25 Figure 1, is a side view in broken section of the shoe of an automobile tire, showing a capsule-type of container with a scored or roughened interior surface and with a ball mounted therein adapted to be frictionally worn by back and forth movements of the same to determine the extent proportionately of actual travel as well as wear of the shoe under any guaranteed mileage claimed for the use of the same. Fig. 2, is a vertical sectional view on the line α , α , of Fig. 1, showing the tell-tale device of my said invention in operative position in the rim portion of the shoe of the automobile tire; and Fig. 3, is a side elevational view of the container 30 device with its removable cap to readily permit of the removing of the rolling body mounted therein to determine from wear thereof at once the extent of use of the shoe of the tire.

40 Referring to the drawings a , is the shoe of the tire having as illustrated in one rim portion a^1 , thereof an oblong chamber a^2 , to receive a capsule-form of container b , having a removable cap b^1 . The internal

surface of the container, is provided with a 50 scored or roughened surface b^2 , for the reception of a ball b^3 , of lead or other more or less soft material, to provide by its constant contact with the scored or roughened surface interior of the said container b , and 55 wear incident thereto, proportionately the extent of travel as well as wear of the shoe and thus whether the shoe has given the required mileage under which it was sold for use and whether the mileage use guaranteed 60 therefor has been realized or not. The wear of the ball against the roughened surface of the container b , will be in proportion to the actual wear of the shoe under whatever usage may be given the same, as has been 65 demonstrated by actual practice of this invention under many miles of usage of the described device in an automobile tire.

Having thus described the nature and object of my invention, what I claim as new 70 and desire to secure by Letters Patent is:—

1. A tell-tale device of the character described, comprising a container with a roughened interior surface and a rolling body mounted therein, substantially as and for 75 the purposes described.

2. A tell-tale device of the character described, comprising a capsule-type of container having a removable cap and a scored or roughened interior surface and a rolling 80 body mounted therein, substantially as and for the purposes described.

3. The combination with an automobile shoe or tire having an oblong chamber formed therein, of a tell-tale device consisting of an oblong container having a cap fitted thereto and having a scored or roughened interior surface and a rolling body mounted in said container, substantially as and for the purposes described. 85

In witness whereof, I have hereunto set my signature in the presence of two subscribing witnesses.

HENRY H. ROBERTS, JR.
